UNITED STATES PATENT OFFICE.

MAXIMILIAN CHARLES SCHWEINERT, OF WEST HOBOKEN, NEW JERSEY, AND HENRY P. KRAFT, OF NEW YORK, N. Y.

WATER-BOTTLE STOPPER.

No. 860,698.

Specification of Letters Patent.

Patented July 23, 1907.

Application filed May 29, 1906. Serial No. 319,248.

To all whom it may concern:

Be it known that we, MAXIMILIAN CHARLES SCHWEINERT, residing in West Hoboken, in the county of Hudson and State of New Jersey, and HENRY P. KRAFT, residing in the borough of Brooklyn, in the county of Kings, city and State of New York, citizens of the United States, have invented certain new and useful Improvements in Water-Bottle Stoppers, of which the following is a specification.

10 This invention relates to water bottle stoppers and aims to provide certain improvements therein. Stoppers of this kind as heretofore constructed have usually consisted of a socket member and a stopper proper which is adapted to screw into or upon the socket member, a suitable packing being carried by the one or other of said parts to form a leak-tight joint between the two. In the best devices of this kind the stopper proper is formed of two pieces of sheet metal, the lower of which is drawn to cup shape and is provided 15 at its upper end with an outwardly extending lateral flange, and the upper of which is formed as a cap or disk, the edge of which is crimped or bent over the flange of the lower member so as to make a tight joint between the two. This construction while providing 20 a strong and durable stopper, has the disadvantage of forming a flange at the top of the stopper which is of considerably greater diameter than the body thereof. This renders the use of such stopper difficult in certain forms of water bottle stoppers wherein the stopper 25 proper is designed to screw below the top of the socket member. In this and other types of stoppers the packing material is formed as a disk which is carried on the under face of the stopper proper, the socket member being formed with a seat against which said 30 disk contacts when the stopper is screwed home. Such packing is liable to distortion as it is pressed between the two metal surfaces and this results in the necessity of frequently renewing the packing in use.

Our present invention obviates these several disadvantages and provides a stopper which is of the same general diameter throughout, and which, while carrying the packing disk on its under face as before, provides means whereby distortion of the packing is prevented. The stopper provided by our invention is 45 also of cheap and durable construction.

In the drawings wherein we have illustrated several embodiments of our invention, Figure 1 is a central vertical section of a hot water bottle provided with a stopper made in accordance with our invention; Fig. 50 2 is a side elevation of the stopper proper removed; Fig. 3 is an enlarged fragmentary section of a portion of the stopper shown in Figs. 1 and 2; Fig. 4 is a central section of a modified form; Fig. 5 is a view similar to Fig. 3 showing a portion of Fig. 4; Fig. 6 is a

central section of a further modification; Fig. 7 is a 55 view similar to Fig. 3 showing a portion of Fig. 6.

Referring to the drawings, let A indicate any suitable form of hot water bottle having a neck *a* and a funnel *b*. The socket member B is vulcanized or otherwise secured to the neck *a* and is formed with an inwardly turned flange *c* constituting a seat for the stopper proper when the latter is screwed down. The stopper C is formed with a body portion *d* and a handle *e* of any suitable construction, that shown being formed of a wire bent to proper shape with its ends 60 riveted to the upper portion of the body *d*.

Our invention is particularly directed to the construction of the body *d*. At present it is customary to form such body *d* of two sheet metal members, the lower of which is cup-shaped with its open side uppermost, such member being provided with a flange which extends outwardly to a considerable distance beyond the side wall of the cup. The upper member is usually formed as a cap or disk of sufficient diameter to extend beyond the flange of the lower 70 member so that its edge may be crimped or bent under such flange to unite the parts. This construction involves a considerable increase in diameter of the stopper at its upper end, so that it is not adapted for use in water bottles in which the stopper proper is 75 designed to screw inwardly beyond the upper edge of the socket member. Such construction also necessarily leaves a somewhat imperfect joint at the top of the stopper, which is difficult to nickel plate.

According to our invention we provide a construction in which the body of the stopper is formed in two parts as before, but in which such parts are so united that the stopper, at their point of connection, shall have no greater diameter than that of its threaded portion, whereby the stopper may screw into the socket member past the end thereof. One form of such connection is made in the manner shown in Figs. 1 to 3 of the drawings, wherein the body *d* of the stopper is constructed of sheet metal and is formed with a cup-shaped upper section *g* and a disk shaped lower section *h*, the edge of the disk *h* being bent inwardly to form a shoulder *y* to prevent relative movement of the section *g* in one direction, and then outwardly to form a flange *i* to prevent such movement in the opposite direction. The edge of the cup *g* is bent inwardly in this construction to form a flange *j* which lies between the shoulder *y* and the flange *i*. In process of construction the disk *h* is first formed and the flange *j* of the section *g* is then turned into the groove formed between the flange *i* and the shoulder *y* of the disk.

Preferably the parts are arranged in the manner shown, that is to say, with the cup *g* forming the upper part of the body of the stopper and the disk *h* forming its

lower part. When so constructed the handle *e* is fastened directly to the threaded portion of the body, so that the strains in use are transmitted to the body through its integral top wall. If the position of the 5 parts is reversed and the handle *e* fixed to the disk *h* or its equivalent, the strains of use would be transmitted through the flanged joint between the parts, and such joint would hence have to be of strong and rigid construction. This is not necessary when the parts are 10 constructed as shown. On the contrary we prefer ordinarily to provide a loose connection between the disk and cup so that the disk shall be free to rotate independently of the cup, this construction being shown in Figs. 1 to 5. In stoppers of this type the packing 15 washer is usually formed as a disk *k* which is carried at the bottom of the stopper, being fixed thereto by a rivet *l*. In previous constructions, when the stopper has been screwed down, the packing washer has been liable to distortion between the rigid under face of the 20 stopper and the seat *c*. By our present invention we prevent such distortion by swiveling the packing disk *k* to the part *g* of the stopper body in the manner just described so that the packing is pressed down upon the seat *c* without rotation. In this construction the 25 disk acts in effect as an antifriction member between the packing and the cup *g*, permitting the latter to rotate without turning the disk.

The stopper provided by our invention is especially adapted for use in connection with the particular type 30 of socket member shown in Fig. 1. In this construction the socket member is extended upwardly a considerable distance beyond the neck *a* of the bottle and is provided with ports or openings *m* through which the bottle may be filled or emptied. During this operation the stopper proper is screwed upwardly to the position shown in Fig. 1 so as to uncover the ports *m*. This construction necessitates that the stopper proper be screwed downwardly a considerable distance below the top of the socket member in order to close the bottle. The formation of the stopper body without a projecting flange permits this action without increasing the length of the stopper.

In Figs. 4 and 5 we have shown a mode of attachment which differs somewhat from that shown in Fig. 1. 45 In these figures the flanges are reversed so that the shoulder *y'* and flange *i'* are formed upon the cup-shaped portion *g* while the flange *j'* is formed on the disk *h*. In this construction the flange *j'* is crowded into the space between the flange *i'* and the body of the portion *g*.

In Figs. 6 and 7 we have illustrated a connection similar to that of Fig. 1, but having the flanges pressed tightly together so as to prevent rotative motion of the disk *h* with relation to the portion *g*.

55 Other modifications may be made without departing from the spirit of our invention. For instance it is not essential that the joint between the parts be made at the lower part of the stopper, or that the stopper consist of two portions only. Neither is it necessary that the 60 particular form of inter-locking flanged joint be used, as any similar means for connecting the parts may be employed. Other modifications may also be made.

What we claim is: —

1. In a water bottle stopper, a stopper having a body 65 portion having external screw threads, said body portion

being formed of a plurality of sections of sheet metal having their edges bent to form interlocking flanges, such flanges being of not greater diameter than the threads of such body portion.

2. In a water bottle stopper, a stopper formed of two 70 pieces of sheet metal, the one a cup-shaped portion and the other a disk at the lower end of such portion, such parts having their edges bent to form interlocking flanges, such flanges being of not greater diameter than the body of such stopper.

3. In a water bottle stopper, a stopper formed of two 75 pieces of sheet metal, the one a cup-shaped portion and the other a disk at the lower end of such portion, such parts having their edges bent to form interlocking flanges, such flanges being of not greater diameter than the body of such stopper, and being loosely engaged whereby to 80 swivel such parts together.

4. In a water-bottle stopper, a stopper having a threaded 85 body portion formed of a plurality of sheet-metal sections having their edges united to form a joint between the sections of not greater diameter than the body of the stopper, the metal at such joint being bent inward and outward to engage the parts and prevent relative movement thereof in either direction.

5. In a water-bottle stopper, a stopper having a threaded 90 body portion formed of two sheet-metal sections having their edges united, one of said sections being formed in cup shape and one being bent to form a shoulder for preventing relative movement of the other in one direction, and having its edge bent to prevent such movement 95 in the opposite direction, the joint between such parts being of not greater diameter than the body of the stopper.

6. In a water-bottle stopper, a stopper having a threaded 100 body portion formed of two sheet-metal sections having their edges united, the upper of said sections being formed in cup shape and the lower as a disk, one of said sections being bent to form a shoulder for preventing relative movement of the other in one direction, and having its edge bent to prevent such movement in the opposite direction, the joint between such parts being of not greater diameter than the body of the stopper.

7. In a water-bottle stopper, a stopper having a threaded 105 body portion formed of two sheet-metal sections having their edges united, the upper of said sections being formed in cup shape and the lower as a disk, the upper of said sections being bent to form a shoulder for preventing relative movement of such disk in one direction, and having its edge bent to prevent such relative movement in the opposite direction, the joint between such parts being of not greater diameter than the body of the stopper.

8. In a water bottle stopper, a stopper having a screw-threaded upper portion, and a lower portion swiveled thereto, said lower portion extending below said upper portion and being adapted to press a packing against a seat. 120

9. In a water bottle stopper, a stopper having a screw-threaded upper portion, a lower portion swiveled thereto, said lower portion extending below said upper portion, and a packing gasket carried by such lower portion.

10. In a water bottle stopper, a stopper having a screw-threaded portion, a packing, and an antifriction member interposed between said packing and screw-threaded portion, said member and packing being swiveled to said screw-threaded portion.

11. In a water bottle stopper, a stopper having a screw-threaded portion, a packing at the lower end of such portion, and an antifriction member between such parts, said packing and member being swiveled to said screw-threaded portion.

12. In a water bottle stopper, a stopper having a metal member swiveled thereto and extending below the body thereof, and a packing carried by such member.

In witness whereof, we have hereunto signed our names in the presence of two subscribing witnesses.
